Primary Examiner — Elizabeth Albert(74) *Attorney, Agent, or Firm* — Rabin & Berdo, P.C.(57) **CLAIM**

I claim the ornamental design for a highlighter pen, as shown and described.

DESCRIPTION

FIG. 1 is a perspective view of a highlighter pen showing my new design;

FIG. 2 is a front view thereof; the rear view is omitted since it is a mirror of the front view.

FIG. 3 is a left side view thereof;

FIG. 4 is a right side view thereof;

FIG. 5 is a top plan view thereof;

FIG. 6 is a bottom plan view thereof; and,

FIG. 7 is an exploded view thereof.
